UNITED STATES PATENT OFFICE.

RICHARD BAKER, OF NEWARK, NEW JERSEY.

MANUFACTURE OF WHITE LEAD BY PRECIPITATION.

Specification of Letters Patent No. 12,616, dated April 3, 1855.

To all whom it may concern:

Be it known that I, RICHARD BAKER, of the city of Newark, in the county of Essex and State of New Jersey, have invented a new and Improved Mode of Making Carbonate of Lead with an Apparatus Adapted to the Purpose, commonly called "White Lead"; and I do hereby declare that the following is a full and exact description 10 thereof, reference being had to the accompanying drawings and to the letters marked thereon.

The nature of my invention consists in controlling the application of the carbonic-acid gas necessary to decompose the sub-acetate of lead in forming carbonate of lead by precipitation, with an apparatus by which the carbonic acid gas is all used, instead of a large portion being lost as in the 20 old way; thereby rendering the precipitating process too expensive, notwithstanding a more superior carbonate of lead can be made by precipitation, than by the common method of corrosion.

Figure 1 is a perspective view of the whole apparatus, for generating the carbonic acid gas, mixing the solutions, applying the gas and completing the process of forming the carbonate, ready to be washed 25 and dried. Fig. 2 is a longitudinal, sectional, elevation showing the internal arrangement of the parts.

As no new method of generating the gas, nor no new materials are here used, in producing the carbonic acid gas, or the sub-acetate of lead, it is deemed unnecessary to describe their composition, as they are well known, to those conversant with making carbonic acid gas, as well as carbonate of 35 lead. They will be spoken of only as connected with the apparatus herein described, and the purpose of the same.

Figs. 1 and 2 represent the plan complete.

Like letters refer to like parts, and pur- 40 poses throughout the drawings. Large letters to the major, and small letters to the minor parts of the apparatus.

I use two solution vessels A A so as to carry on the mixing and settling of the 45 solution as one can be charged and set to work, while the other is being drawn off. In these vessels are placed water, sugar of lead, and protoxid of lead properly proportioned. The thicker part is allowed to settle, and the clear liquid solution is drawn off through the faucets a a and conducted by

the pipes b, b, down into the pump cistern B. The solution is sub-acetate of lead at this stage of the proceeding. It is pumped up by the pump C and conveyed by the pipes c c into the precipitator D which is filled to near the top with the solution, and is ready to be acted upon by the carbonic acid gas. The precipitator is closed to prevent leakage. In the generator E is placed 50 carbonate of lime or chalk, and water. In the top of this generator is placed a small vessel d to hold sulfuric acid, having a small hole in the side, opening into the generator. In the upper part of this small vessel, is placed a solid plunger e attached to a screw passing through a nut in the top of the same. By means of this screw, the plunger can be depressed by degrees, which causes a small quantity of the acid, to pass 55 through the hole in the side, and drop on the lime. It is necessary to apply the acid slowly, and in small quantities, in order to give the lime, time to absorb the acid, so as to not produce a dangerous pressure. The 60 sulfuric acid is introduced into the small vessel through a hole in the top which is stopped with a screw stopper, as the pressure of the gas would be likely to blow out an ordinary stopper. To facilitate the 65 decomposition of the lime, I use an agitator f being a vertical shaft fixed in the center of the generator, having attached to its lower end, blades g, so arranged as to extend to near the side of the generator. On the upper part of this shaft is a screw which 70 works in a suitable nut in the top of the generator, at the top is placed a crank h to revolve the blades, thus mixing the sulfuric acid and lime, which with the elevation and depression produced by the screw, facilitates 75 the operation, producing a larger quantity of gas, with less waste than otherwise. The 80 gas rises up and passes through the pipe i and so on down into the water j in the wash vessel K, here it is washed by a small quantity of water, and rises up into the upper part of the vessel K and thence through the 85 pipe l and into the vessel D. The pipe l is intended merely to pass through the head 90 of the vessel D and not to come in contact with the solution as the gas rises up through the pipe l and collects in the space m and from this space is drawn through the pipe 95 n n through the force pump G and by its 100 action is forced through the tube O and its branches, into the solution to allow the solu- 105 110

tion to absorb a portion, the balance rising and being operated upon again in the same manner, until the solution has absorbed all it can; thus becoming decomposed, and producing carbonate of lead.

The several stages of the process are known, and determined by the aid of the hydrometer, and known chemical equivalents, which can be calculated sufficiently correct, 10 to insure success.

I prefer applying the carbonic acid gas to the solution, in preference to applying the solution to the gas by shower or otherwise, as time is necessary for the solution to absorb the gas. It also thickens, and has a 15 tendency to foam, which also makes it difficult to apply to the gas, besides the effect is not so good. After the complete decomposition of the solution, the carbonate of lead is precipitated to the bottom, and leaves the clear liquid acetate of lead to be drawn off through the faucets near the bottom, (hid in the drawing by the leader,) for removing the carbonate, and conveyed through the 20 pipe *q*, seen in Fig. 2 into the pump cistern *B* and is pumped up into the solution vessels *A A* and is ready to be re-charged for the next operation. The carbonate of lead is 25 drawn out of the precipitator, at the opening *r r* and is conducted through the pipe *s s* into the receiving vessel *H*, where it is left for the mother water to withdraw from the carbonate and the fluid is drawn off from time to time as the progress of the 30 separation will permit, through the faucets *t t* &c. It is then ready for the washing. The neutral salts being all washed out. After 35 this it is dried very gradually in order to prevent discoloration. To soften the carbonate, a little saleratus is used in the washing.

The residuum which will collect in time in the solution vessels *A A* can be removed, by a hot solution of sugar of lead, and water 45 which will dissolve the protodox of lead, which will permit the same to be drawn off into the pump cistern below, and be used in the next process. The residuum in the generator when exhausted is to be removed 50 through the aperture *u* and may be used for some other purpose, as it is of no further use, in generating carbonic acid gas. The generator *E* washing vessel *K* precipitator *D* and pump *C* including their 55 connections, are all closed, to prevent the

leakage of the carbonic acid gas, that none be lost by exposure to the atmosphere I I I are the stands and floor, by which the apparatus is supported.

There is to be attached to the apparatus 60 an airtight gas bag or expansion balloon furnished with a stop cock (which has hitherto been omitted in the specification and is moreover an essential part of the apparatus). The stop cock of the balloon is to be 65 screwed into the head of the precipitator or vessel *D* in any convenient part thereof. The balloon may be suspended from the ceiling of the room. The use of the balloon is to collect and retain the carbonic acid gas 70 until entire absorption has taken place, being in communication with the space *m* in the vessel *D*) when it will return from an inflated to a collapsed condition, showing very accurately the rate of absorption. The 75 use of the stop cock is to shut off the communication between the balloon and precipitator or vessel *D*, as in case of accident or leakage the gas may be sustained in the balloon until any difficulty is adjusted. 80

What I claim as my invention, and desire to secure by Letters Patent, is—

1. An improvement in the combination of apparatus so arranged and constructed as to produce carbonate of lead by precipitation more expeditiously and economically than by any other arrangement heretofore used for the same purpose. 85

I do not claim each and every part of the apparatus herein described as new, I claim 90 connecting with an air pump a series of vertical distribution pipes *o o o* as herein described in specification consisting of a great many in number descending vertically from the main horizontal pipe *O* and passing 95 down through the head of the precipitating vessel *D*—into the solution of subacetate of lead 1 pipe at least through each square foot of surface of the top of the precipitating vessel thereby traversing the solution with 100 a great number of small jets or blasts of carbonic acid gas causing a very rapid decomposition of the solution as the vertical pipes cannot choke up with the ponderous precipitate a constant blast from each pipe 105 is thereby insured.

RICHARD BAKER.
